ROOF CONSTRUCTION

Arthur S. Mellinger, Indianapolis, Ind.

Application September 26, 1939, Serial No. 296,691

1 Claim. (Cl. 108—1)

This invention relates to roof construction, and aims to provide a curved roof structure which is exceptionally strong, and one which will be free of truss rods, commonly employed in roofs.

A further object of the invention is to provide a curved roof construction wherein the weight of the roof will be equally distributed throughout the entire surface thereof.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

20 Referring to the drawings:

Figure 1 is a plan view illustrating a roof constructed in accordance with the invention, the sheathing as partially covering the rafters of the structure.

25 Figure 2 is a side elevational view thereof.

Figure 3 is a sectional view taken on line 3—3 of Figure 2.

Referring to the drawings in detail, the roof structure embodies end members 5 that have 30 their upper surfaces curved in the arc of a circle, as clearly shown by Figure 3 of the drawings.

Bars 6 connect the end members 5 at points near the lower edges thereof, the bars 6 having beveled upper surfaces. Connecting the bars 6, 35 are rods 7 that are supplied with nuts 8 at their ends, whereby the rods may be securely held in openings of the bars 6, to prevent spreading of the roof, under excessive weight.

Rafters 9 are arranged in parallel spaced relation with respect to each other, and extend 40 throughout the entire distance between the end members 5.

These rafters 9 are covered by sheathing strips 10 that are diagonally disposed, as shown by 45 Figure 1 of the drawings. Another layer of sheathing strips indicated at 11 covers the sheathing strips 10, the strips 11 being disposed diagonally in a direction opposite to the diag-

onal sheathing strips 10, and completely covering the sheathing strips 10.

The number of layers of sheathing strips 10 and 11, will of course be governed by the size of the roof under construction, and the number 5 of layers of sheathing strips is not limited to two as shown in the drawings.

It might be also stated that the number of rods employed in bracing the roof against lateral spreading, may be varied according to the 10 length of the roof. In this connection, it might be stated that the rods are spaced preferably fifteen feet apart, and the size of the rods will of course be varied according to the weight of the structure.

Due to the construction shown and described it will be obvious that I have provided a roof construction which is exceptionally cheap to manufacture, and one wherein truss rods are eliminated. It is further pointed out that when 20 the ceiling has been positioned over the inner surfaces of the rafters 9, all shoulders and girders which ordinarily catch sound waves to cause echoes, are eliminated providing a roof of exceptional acoustic qualities. A roof of this structure also lends itself to the insulation of the 25 roof, since the nature of a curved surface causes an unequal pressure of the sun's rays, which causes air currents at the surface of the roof which dissipate the heat.

30 What is claimed is:

An arched roof construction, comprising end members having curved upper edges, parallel bars connected with the end members near the lower ends of the curved upper edges, truss rods connecting said bars, spaced parallel rafters having their ends connected to the upper curved edges of the end member, a layer of sheathing strips bent over the rafters in engagement with the rafters and disposed at oblique angles with respect to the parallel bars, a layer of sheathing strips bent over the first mentioned sheathing strips and disposed at oblique angles with respect to the parallel bars and the last mentioned sheathing strips crossing the first mentioned sheathing strips and contacting therewith, bracing the rafters and end members.

ARTHUR S. MELLINGER.
